MAGNETIC TOOL

Marcial M. Sanchez, Alamogordo, N. Mex.

Application May 2, 1949, Serial No. 90,910

2 Claims. (Cl. 81—15)

1

This invention relates to a tool, and more particularly to a tool for use in straightening dented vehicle fenders, door panels, and the like.

The object of the invention is to provide a tool which will enable the user to readily straighten dents in vehicle door panels or fenders, the tool of the present invention being capable of straightening dents which are incapable of being straightened by a conventional hammer in view of the inaccessibility of such dents.

Another object of the invention is to provide a dent straightening tool embodying a magnet which securely attaches the tool to the dented portion, the tool further including a sliding hammer which is adapted to produce a sharp shock or hammer blow to thereby straighten the dent.

A further object of the invention is to provide a tool which is extremely simple and inexpensive to manufacture.

Other objects and advantages will become apparent during the course of the following description.

In the accompanying drawings, forming a part of this application, and in which like numerals are used to designate like parts throughout the same:

Figure 1 is an elevational view of the tool, according to the present invention;

Figure 2 is a view similar to Figure 1, but with certain parts of the tool in section;

Figure 3 is a sectional view taken on the line 3—3 of Figure 2;

Figure 4 is a sectional view taken on the line 4—4 of Figure 2; and

Figure 5 is a view showing the use of the tool for straightening a dent in a vehicle door panel.

Referring in detail to the drawings, the numeral 10 designates a bar or rod which may be fabricated of any suitable material such as steel and the bar 10 may be cylindrical in shape. Mounted on one end of the bar 10 is a magnetic head 11 which has a conventional structure and includes a coil 12. A line or cable 13 is connected to the magnetic head 11 and the line 13 has a plug 14 for insertion in a wall socket 15, Figure 5, whereby the head 11 is connected to a source of electrical energy for energizing the latter.

Secured to the other end of the bar 10 is a handle 16 which is adapted to be gripped in the user's hand for steadyng the tool during the use thereof. Further, by pulling on the handle 16, small dents may be removed from door panels and the like. Arranged contiguous to the handle 16 and secured to the bar 10 is a stop member 17.

Mounted for movement into and out of contact with the stop member 17 is a hammer 18 which may be made of steel or other suitable material. The hammer carries a tubular bushing 19 which is fabricated of a non-magnetic material, the bushing 19 being slidably arranged on the bar 10.

In use, the tool is especially suitable for

2

straightening dents such as the dented or damaged portion 21 of the door panel 20, Figure 5. Thus, to remove the dent 21 with an ordinary hammer would be impossible or could only be done with great difficulty. However the tool of the present invention enables the user to readily remove the dent 21 and this is accomplished without the necessity of disassembling the door panel 20 in order to gain access to the dented portion 21. The user merely inserts the plug 14 into a suitable socket 15 to thereby energize the magnetic head 11. Then, the head 11 is arranged in engagement with the dented portion 21 so that the magnetic head 11 becomes securely attached to the dented portion 21. Next, the operator manually forces the hammer 18 against the stop member 17 to form a sharp impact or hammer blow when the tool is in use. One or more of such impacts is usually sufficient to remove the dent 21 from the member 20.

The tool is especially useful in repairing members which are hard to get at and the various parts of the tool can be made of any suitable material. The tool can also be made with a permanent or electro-magnet and can be made so that it will operate on A. C. D. C., or can be actuated by means of a suitable battery.

What I claim:

1. In a tool, a bar, a magnetic head mounted on an end of said bar, a stop member mounted on the other end of said bar, a hammer slidably arranged on said bar and adapted to strike said stop member, a handle arranged contiguous to said stop member and secured to the said bar, and a non-magnetic bushing carried by said hammer and slidably embracing said bar.

2. A tool for straightening dented portions of a member, comprising a bar, a magnetic head mounted on one end of said bar for engagement with the dented portion of said member, a line for connecting said head to a source of electrical energy, a hand engaging handle secured to the other end of said bar, a stop member arranged contiguous to said handle and mounted on said bar, a hammer adapted to strike said stop member, and a non-magnetic bushing carried by said hammer and slidably embracing said bar.
